TURBINE ROTOR

Reinout P. Kroon, Swarthmore, Pa., assignor to Westinghouse Electric & Manufacturing Company, East Pittsburgh, Pa., a corporation of Pennsylvania

Application January 31, 1939, Serial No. 253,750

2 Claims. (Cl. 253—69)

My invention relates to steam turbines of the type wherein the rotor is made hollow for the passage of steam and it has for an object to provide means to prevent water condensing from the steam from accumulating in the hollow and causing unbalance and serious distortion resulting in vibration.

A further object of my invention is to provide, in connection with a steam turbine rotor having a bore for the passage of steam, a thin-walled metallic sleeve carried internally of the bore and spaced from the interior wall of the latter to prevent direct contact, with the rotor proper, of water condensing from the steam and which would otherwise set up unbalance and distortion of the massive rotor with serious unbalance and vibration.

These and other objects are effected by my invention as will be apparent from the following description and claims taken in connection with the accompanying drawing, forming a part of this application, in which the figure is a longitudinal sectional view of a turbine embodying my improvement.

Referring to the drawing more in detail, there is shown a casing embodying, for example, an intermediate section 10 and end or exhaust sections 12, 12 secured in any suitable manner to the two opposite ends of the section 10. A rotor 13 is supported for rotation within the casing structure by means of bearings 14, 14 carried by the end or exhaust casing sections 12, 12. As shown, the rotor includes end members 15, 15 spigoted within and secured to opposite ends of the intermediate portion 16 having a hollow or bore 17.

The blading of the turbine illustrated comprises a high-pressure section, at 18, and axially-aligned, low-pressure sections, at 19 and 20, the high-pressure section including impulse blading 21 and reaction blading 22 and the low-pressure sections, at 19 and 20, including reaction blading, at 23 and 24, respectively.

Steam supplied to the turbine passes in series through the impulse blading 21 and the reaction blading 22 of the high-pressure section, at 18, and steam exhausted from the latter passes in parallel through the low-pressure sections, at 19 and 20, the steam entering the exhaust space, at 25, being directly supplied to the low-pressure section, at 19, and being supplied to the low-pressure section, at 20, through the bore 17 of the intermediate rotor portion 16, the latter having inlet openings 26 communicating with the space, at 25, and outlet openings 27 communicat-

ing with the space, at 28, which supplies steam to the low-pressure section, at 20.

With a turbine of this type, as the rotor and the hollow portion thereof may be of considerable length and as opportunity exists for the condensation of water from the steam passing through the hollow portion of the rotor, accumulations of water may occur therein and cause unbalance and serious rotor distortion resulting in violent vibration.

In accordance with the present invention, the hollow portion of the rotor is provided with a thin-walled metallic, co-axial sleeve 30 carried by end rings 31 and fixed within the bore 17. The liner or tubular member 30 is spaced from 18 the bore wall with the result that water accumulations act thereon and not on the rotor proper, whereby distortions of the latter, and consequent vibrations are avoided. Preferably, the tubular member diverges in the direction of flow 20 to facilitate the passage of water condensing from the steam in the direction of flow. The anchor or end rings 31 and 32 provide for support of the liner or tube with requisite divergence of the latter, but, as the tube or diffuser has a relatively 25 thin wall, has relatively small mass, and is spaced from the interior of the rotor, it cannot transmit any appreciable distorting forces to the rotor proper even though it should be unevenly heated by the fluid passing therethrough or should 30 be distorted by water accumulations.

While I have shown the improvement applied to the hollow portion of the relatively long rotor of a double-flow steam turbine, it will be apparent that it may be applied to any steam turbine rotor which is made hollow for the passage of steam, the only requirement being that, instead of having the steam pass directly in contact with the bore wall of the hollow portion, a liner or diffuser shall be provided for the bore, to prevent accumulations of water in the rotor 40 sufficient to develop disturbing forces causing distortion and vibration.

While I have shown my invention in but one form, it will be obvious to those skilled in the art that it is not so limited, but is susceptible of various changes and modifications without departing from the spirit thereof, and I desire, therefore, that only such limitations shall be placed thereupon as are imposed by the prior art or as 50 are specifically set forth in the appended claims.

What I claim is:

1. In a steam turbine, a casing, a rotor, high- and low-pressure blading sections carried by the casing and by the rotor; said rotor having a hol-

55

low portion bounded by the high-pressure blading section and having openings communicating with the hollow portion to provide a passage for conducting steam from the discharge end of 5 the high-pressure blading section to the inlet end of the low-pressure blading section; and means for preventing distortion and unbalance of the rotor by condensate collecting from the steam on the interior wall of the hollow portion 10 and comprising a thin metallic sleeve bounding the steam flow passage of the hollow portion; said sleeve being spaced from the interior wall of the hollow portion, extending for substantially the full length of the high-pressure blading 15 section, and having its ends fastened to the interior hollow portion.

2. In a steam turbine, a high-pressure blading section; a pair of low-pressure blading sections aligned axially with the high-pressure blading 20 section; a casing carrying the stationary blading of said sections; a rotor carrying moving

blading of said sections and having the portion thereof carrying the high-pressure moving blading provided with an axial bore; said casing and rotor providing a steam space with which the exhaust end of the high-pressure section and 5 the inlet end of one of the low-pressure sections directly communicate; said rotor having openings affording communication of said space with the bore and openings affording communication of the bore with the inlet end of the last-named 10 low-pressure section; and means for preventing distortion and unbalance of the rotor by condensate collecting from the steam on the interior wall of the bore and comprising a thin metallic sleeve bounding the steam flow passage of the 15 bore; said sleeve being spaced from the interior wall of the bore, extending for substantially the full length of the high-pressure blading section, and having its ends fastened to the interior wall of the bore.

20

REINOUT P. KROON.
